CLAIM

The ornamental design for an LED beacon, substantially as shown and described.

DESCRIPTION

FIG. 1 is a first top isometric view of an LED beacon, which is shown mounted in a base;

FIG. 2 is a top plan view thereof;

FIG. 3 is a left side elevational view thereof, the right side being a mirror image;

FIG. 4 is a rear elevational view thereof;

FIG. 5 is a front elevational view thereof; and,

FIG. 6 is a second top isometric view thereof, showing the LED beacon mounted on a pipe instead of the base of FIG. 1.

In the figures, the broken lines show environmental structures forming no part of the claimed design.
